(57) **CLAIM**

The ornamental design for eyeglasses, sunglasses, or like eyewear, as shown and described.

DESCRIPTION

FIG. 1 is a perspective view of eyeglasses, sunglasses, or like eyewear showing my new design;

FIG. 2 is a front elevation view thereof;

FIG. 3 is a rear elevation view thereof; and

FIG. 4 is a top plan view thereof;

FIG. 5 is a bottom plan view thereof;

FIG. 6 is a left side elevation view thereof, the right side elevation view being a mirror image;

FIG. 7 is side elevation cross-section view thereof taken along line 7-7 in FIG. 4;

FIG. 8 is an enlarged perspective view of a portion thereof indicated in FIG. 1;

FIG. 9 is an enlarged top plan view of a portion thereof indicated in FIG. 4;

FIG. 10 is an enlarged bottom plan view of a portion thereof indicated in FIG. 5;

FIG. 11 is an enlarged side elevation view of a portion thereof indicated in FIG. 6;

FIG. 12 is an enlarged side elevation view of a portion thereof indicated in FIG. 7;

FIG. 13 is an enlarged perspective view of the internal components of a portion thereof indicated in FIG. 1;

FIG. 14 is an enlarged top plan view of the internal components of a portion thereof indicated in FIG. 4;

FIG. 15 is an enlarged bottom plan view of the internal components of a portion thereof indicated in FIG. 5;

FIG. 16 is an enlarged side elevation view of the internal components of a portion thereof indicated in FIG. 6; and, FIG. 17 is an enlarged side elevation view of the internal components of a portion thereof indicated in FIG. 7.

The broken lines immediately adjacent shaded areas represent bounds of the claimed design and environment while all other broken lines are directed to environment and are for illustrative purposes only. The broken lines form no part of the claimed design.

The internal components in FIGS. 13-17 are shown separately for ease of illustration only.
